[57] CLAIM

The ornamental design for a seat, as shown and described.

DESCRIPTION

FIG. 1 is a perspective view of a seat showing my new
design;
FIG. 2 is a front elevational view thereof;
FIG. 3 is a top plan view thereof;
FIG. 4 is a right side view thereof, the opposite side being
a mirror image of the side shown; and,
FIG. 5 is a rear elevational view thereof.
